UNITED STATES PATENT OFFICE

JOSEF MEISER, OF DORTMUND, GERMANY

SHEET PILING IN BOX FORM

Application filed July 10, 1929, Serial No. 377,241, and in Germany May 31, 1928.

In constructing sheet piling in box form from metal plates and interposed I-sections, with plain connections of the usual type, difficulties in ramming arise from the tolerances allowed in rolling the plates.

According to the present invention and with the object of avoiding such difficulties, the connections at one side of the wall (the exposed side) are arranged to fit closely, whilst those on the opposite side are designed in such a way as to leave sufficient room for the plates constituting that side to yield in the direction of the wall without endangering the stability of the latter.

If desired or if found necessary, channel members can be inserted in the wall, to provide balanced ramming and to afford spaces for accommodating structural members.

Typical embodiments of the invention are illustrated by the accompanying drawing whereon Fig. 1 represents a cross section of one form and Fig. 2 a similar view of a slightly modified form.

As shown, the wall consists of two rows of metal plates *a* and *b*, with interposed I-section members *c*. The plates *a* are connected together by closely fitting joints *d* in known manner; but the plates *b* on the opposite side of the box wall are each provided at one end with a projection *e* behind which engages the offset end *f* of the adjoining plate. The connection *e:f* precludes lateral slipping while affording the possibility for slip to occur in the longitudinal direction of the wall so as to counteract the irregularities that are inevitable in the rolling of the various plates. Said connection may, of course, be of a different design, the essential point being the possibility of movement in the longitudinal direction of the wall.

The wall shown in Fig. 2 is the same as that shown in Fig. 1, except that a channel member *g* is inserted to provide balanced ramming and for the accommodation of structural members. In this case the wall can be closed towards the rear by an iron plate *h*, but this is unnecessary in most instances.

I claim:

1. A sheet piling wall of box formation comprising spaced rows of metal plates,

girder members interposed between said rows, jointing means integral with the plates of one row to provide close-fitting connections between said plates, and jointing means integral with the plates of the other row permitting relative movement in the longitudinal direction of the wall.

2. A sheet piling wall of box formation comprising spaced rows of metal plates, girder members interposed between said rows, a channel member inserted in one row, jointing means integral with the plates of one row to provide close-fitting connections between said plates, and jointing means integral with the plates of the other row permitting relative movement in the longitudinal direction of the wall.

3. A sheet piling wall of box formation comprising spaced rows of metal plates, I-sections interposed between said rows, jointing means integral with the plates of one row to provide close-fitting connections between said plates, and jointing means integral with the plates of the other row permitting relative movement in the longitudinal direction of the wall.

4. A sheet piling wall of box formation comprising spaced rows of metal plates, I-sections interposed between said rows, a channel member inserted in one row, jointing means integral with the plates of one row to provide close-fitting connections between said plates, and jointing means integral with the plates of the other row permitting relative movement in the longitudinal direction of the wall.

In testimony whereof I affix my signature.
JOSEF MEISER.
